UNITED STATES PATENT OFFICE.

WILLIAM A. SPRING, OF BROOKLYN, NEW YORK, ASSIGNOR TO BIGELOW CARPET COMPANY, A CORPORATION OF MASSACHUSETTS.

DESIGN FOR A RUG.

45,503.

Specification for Design.

Patented Mar. 24, 1914.

Application filed February 3, 1914. Serial No. 816,358. Term of patent 3½ years.

To all whom it may concern:

Be it known that I, WILLIAM A. SPRING, a citizen of the United States, residing at Brooklyn, in the county of Kings and State of New York, have invented a new, original, and ornamental Design for a Rug of Carpet Sizes, of which the following is a specification, reference being had to the accompanying drawing, forming part thereof.

The drawing illustrates one quarter of a rug, showing my new design, the remaining three quarters become duplicates there-

of, when the one quarter shown in in the drawing is reversed bi-symmetrically from the central axes, both horizontal and vertical.

I claim:

The ornamental design for a rug, substantially as shown.

WILLIAM A. SPRING.
